UNITED STATES PATENT OFFICE.

THOMAS W. HELLIWELL, OF BRIGHOUSE, COUNTY OF YORK, ENGLAND.

GLAZING THE ROOFS OF HORTICULTURAL STRUCTURES.

SPECIFICATION forming part of Letters Patent No. 284,421, dated September 4, 1883.

Application filed May 3, 1882. (No model.) Patented in England February 13, 1879, No. 570.

To all whom it may concern:

Be it known that I, THOMAS WILLIAM HELLIWELL, of Brighouse, in the county of York, England, have invented certain Improvements in Means for Securing Glass, Slates, &c., to the Roofs and other parts of Buildings, of which the following is a specification.

My invention is especially adapted to securing plates or panes of glass to the roofs and sides of horticultural structures, and I will describe it herein as applied to that purpose.

The novel features of the invention will be more particularly set forth hereinafter.

In the drawings, which serve to illustrate my invention, Figure 1 is a general perspective view of a fragment of a roof constructed according to my invention, and Fig. 2 is a longitudinal section of the roof. Figs. 3 and 4 illustrate slight modifications, which will be referred to more particularly hereinafter.

The plates or panes of glass forming the roof overlap in the manner of shingles or slates, and their lateral edges are clasped between metal strips of peculiar construction, which run from the eaves to the ridge of the roof.

A represents an upper and B a lower pane of glass, the two overlapping at x.

C is one of the purlins upon which the roof structure rests.

D is a strip of metal corrugated longitudinally, as best shown in Fig. 2, its elements comprising an arched central rib, a, which projects upward between the panes of glass, two lateral lower ribs, b b, on which the panes rest, and two exterior lateral troughs, c c, the outer walls, c' c', of which do not rise high enough to touch the glass. There are also two lateral troughs, d d, which are overhung by the edges of the panes of glass. This supporting-strip D extends by preference from the eaves to the ridge of the roof.

The glass is held in place on the seats or ribs b b by means of sheet-metal cap-strips E, which are arched at the center and have their lateral edges curved upward to form troughs e e. The strip E rests on the crown of the arch of rib a, and is secured in place by some good means—as, for example, by a bolt and nut, f, as shown at the left in Fig. 2, by a T-piece and nut, f', as shown at the center of

Fig. 2, or by means of a pin and gib or key, f'', as shown at the right in Fig. 2.

In Fig. 3 I have shown the bolt which secures the cap-strip E in place as passing down through a metal purlin, and in Fig. 4 I have shown the screw as passing down into the sash-bar M of an ordinary skylight or hot-house roof.

For the purpose of separating the two panes of glass where they overlap, in order to better carry away the moisture, I place between them a thin strip, F, of wood, metal, or other suitable material. The moisture that collects in the space g above said strip is thus led into the troughs d in the strip D, and flows off, thereby preventing the dripping of moisture in the interior of the building.

In order to make such glazed structures dust, air, and water tight, I place between the overlapping edges of the glass, back of the strip F, a packing-strip, G, of rubber or other suitable yielding material. If the packing-strip be composed of absorbent material, it will absorb the condensed water and give it off by evaporation.

A washer of rubber is placed about the bolt f, that secures the strips D and E together, between said strips, to prevent leakage and to assist in holding the bolts in place while the nuts are being screwed thereon.

The cap-strips E may be in short lengths, and be made to overlap each other, as shown in Fig. 1. As they are usually made from zinc or other elastic metal, they can be made to fit down snugly on the glass. The troughs or spouts e in these serve to lead off the water, and their convex under sides press elastically on the glass. Any water that passes under the lateral edges of E from the upper side of the glass will flow off through the trough d in D, and any water formed on the under side of the glass by condensation, or which overflows under the glass from d, will be caught in e and carried off.

It will be seen that I do not allow the outer wall, c', of trough c to rise high enough to touch the glass. The object of this is to prevent the water which gathers on the under side of the glass from flowing over the lower or exterior face of trough c and dripping into the building.

Structures of this character may be very readily erected and removed, and are very durable.

I may apply my construction to the sides as well as the roofs of structures, and may use it for covering with slates, metal plates, &c., as well as with glass.

Having thus described my invention, I claim—

- 10 1. The combination, with the covering plates or panes, of the cap-strip E and the supporting-strip D, the latter provided with an arched rib, a, lateral troughs d d, lower ribs, b b, to support the panes or plates, and 15 exterior troughs, c c, the outer sides of which do not extend up to the panes, substantially as set forth.
2. As a means for supporting and securing the lateral edges of the plates or panes, the 20 supporting-strip D, made from sheet metal,

and comprising the elements a, b, c, c', and d, and the cap-strip E, constructed of elastic sheet metal, and having a central arched portion to rest on the strip D, and two lateral troughs, e e, to press elastically on the plates 25 or panes, substantially as set forth.

3. The combination, with the overlapping panes, and means, substantially as described, for supporting and securing their lateral edges, of the packing-strip G, arranged substantial- 30 ly as and for the purposes set forth.

In witness that I claim the foregoing I have hereunto set my hand this 18th day of October, 1881.

THOS. W. HELLIWELL.
